GARMENT

William Doniger, Lawrence, N. Y., assignor to
 David D. Doniger & Co., New York, N. Y., a
 corporation of New York

Application July 28, 1932. Serial No. 625,349

2 Claims. (Cl. 2—253)

My invention relates to a new and useful sports garment, and it relates more particularly to a novel construction therein, whereby certain articles may be suitably protected in the garment 5 while in use.

It is an object of my invention to provide a sport garment whereby tobacco, a pipe or other smoking requirements or accessories or the like, may be properly stored and kept within the garment, and whereby the use thereof may be facilitated.

A further object of my invention is to provide a sport garment with a pocket construction having a humidor effect, particularly for carrying tobacco and smoking accessories.

With the above and other objects in view, my invention consists of a sport garment including a pocket having outer walls of leather, and inner walls of fabric and rubber and having a concealed 20 fastener which will form a continuous closure for the pocket.

My invention further consists of other novel features of construction which will appear more fully from the following detailed description.

For the purpose of illustrating my invention, I have shown in the accompanying drawing one form thereof which is at present preferred by me, since the same has been found in practice to give satisfactory and reliable results, although it 30 is to be understood that the various instrumentalities of which my invention consists can be variously arranged and organized and that my invention is not limited to the precise arrangement and organization of the instrumentalities as 35 herein shown and described.

Referring to the drawing in which like reference characters indicate like parts:

Figure 1 represents a perspective view of the garment embodying my invention, shown in use.

Figure 2 represents a perspective view of the same on an enlarged scale, showing the pocket and its various compartments open.

Figure 3 represents a front elevational view of the pocket construction with the front wall of the pocket removed, and with a part of the inner wall also removed to expose to view the interior construction.

Figure 4 represents a section on line 4—4 of Figure 3, on a somewhat enlarged scale.

The garment 5 of my present invention consists of a body 6 of leather, which has a pocket opening 7 formed therein at a suitable point for the formation of the pocket 8.

The main compartment of the pocket 8 is 55 formed of the outer wall 9 and an inner wall 10

of leather, the latter wall being formed of a patch sewed to the walls 6 of the garment as indicated particularly in Figure 4.

Within the main compartment 11 of the pocket, I provide a humidor compartment 12, preferably 60 of the same width as the main compartment 11, but of a lesser depth as indicated particularly in Figures 3 and 4. This compartment is formed of the outer and inner water-proofed walls 13 and 14, of rubberized fabric or similarly water-proofed material, the two side edges and bottom edge of which are sewed to the inner leather panel 10 of the main compartment by a line of sewn stitches indicated by 15.

To the upper edges 16 and 17 of the water-proofed plies 13 and 14, the two halves 18 and 19 of an interlocking link type slide fastener are secured by lines of sewn stitches 20 and 21;—said fastening device including the slide 22 and the handle 23 thereof, by means of which the 75 humidor compartment 12 may be completely opened or closed at will.

Adjacent the outer wall 13 of the humidor compartment 12, a chamois ply 24 is provided, which extends from the horizontal line of stitches 80 20 to the bottom of the main compartment over part of its width, as indicated at 25, and which over the remaining portion of its width, indicated by 26, extends only to the line of stitches 15. An opening 27 is provided in the chamois panel 25, 85 and a flap 28 is provided over said opening. By this means, a pipe compartment 29 is formed between the outer wall 13 of the humidor compartment 10 and the chamois ply 24.

An outer flap 30 is also provided, affixed by the row of stitches 21, which normally is adapted to close the main pocket opening 7, thereby completely concealing the slide fastener of the humidor compartment 12 and the flap 28 of the 95 pipe compartment.

By this novel construction, the garment is adapted to carry all the smoking accessories within one main pocket, with the tobacco suitably protected from the elements, and yet without the same being visible externally, and without the main pocket being obstructed, since the main pocket compartment 11 is still free for the reception of other articles as may be generally used in sports.

It will thus be seen, that according to my invention, I provide a pocket which is subdivided into several compartments, one of which is water-proofed and closed completely by a slide fastener, and others of which are closed by flaps, with the 105 110

main flap of the main compartment completely concealing all the compartments.

In the illustrations in the drawing, 31 represents a smoking pipe, the bowl 32 of which projects down into the lower portion 33 of the pipe compartment, while the tobacco is indicated at 34, in the humidor compartment 12.

I am aware that my invention may be embodied in other specific forms without departing from the spirit or essential attributes thereof, and I therefore desire the present embodiment to be considered in all respects as illustrative and not restrictive, reference being had to the appended claims rather than to the foregoing description to indicate the scope of the invention.

Having thus described my invention, what I hereby claim as new and desire to secure by Letters Patent, is:

1. A sport jacket, including an outer pocket, two juxtaposed inner walls within the same, formed of water-repellent fabric affixed to each other along their sides and bottom, and open along their upper edges, forming a tobacco compartment within said pocket of lesser depth than the outer pocket, an interlocking-link type slide fastener having the two rows of links thereof secured, respectively, to the two opposed edges of said upper opening of said juxtaposed water-repellent fabric walls, a closure slide intermediate said two rows of links of the fastener for opening and closing the upper free edges of said water-repellent walls, a pipe compartment within said pocket having a greater depth than said tobacco compartment and having a portion thereof narrower than said tobacco compartment and adapted to support a pipe in a generally upright position, a main pocket compartment intermediate said compartments and the outer wall of the jacket, and an outer flap disposed in operative relation to said outer pocket and adapted to extend over the upper opening of said pocket as well as the openings of said tobacco and pipe compartments therein.

35

depth than said tobacco compartment and having a portion thereof narrower than said tobacco compartment and adapted to support a pipe in a generally upright position, and an outer flap disposed in operative relation to said outer pocket and adapted to extend over the upper opening of said pocket as well as the openings of said tobacco and pipe compartment therein. 80

2. A sport jacket, including an outer pocket, two juxtaposed inner walls within the same, formed of water-repellent fabric affixed to each other along their sides and bottom, and open along their upper edges, forming a tobacco compartment within said pocket of lesser depth than the outer pocket, an interlocking-link type slide fastener having the two rows of links thereof secured, respectively, to the two opposed edges of said upper opening of said juxtaposed water-repellent fabric walls, a closure slide intermediate said two rows of links of the fastener for opening and closing the upper free edges of said water-repellent walls, a pipe compartment within said pocket having a greater depth than said tobacco compartment and having a portion thereof narrower than said tobacco compartment and adapted to support a pipe in a generally upright position, a main pocket compartment intermediate said compartments and the outer wall of the jacket, and an outer flap disposed in operative relation to said outer pocket and adapted to extend over the upper opening of said pocket as well as the openings of said tobacco and pipe compartments therein. 90
